(57) **CLAIM**

The ornamental design for a cutting tool, as shown and described.

DESCRIPTION

FIG. 1 is a front view of a cutting tool of the present design; FIG. 2 is a rear view thereof; FIG. 3 is a right side view thereof; FIG. 4 is a left side view thereof; FIG. 5 is a top view thereof; FIG. 6 is a bottom view thereof; FIG. 7 is a first perspective view thereof; FIG. 8 is a second perspective view thereof; FIG. 9 is a third perspective view thereof; FIG. 10 is a first referential view showing the state in use thereof; and, FIG. 11 is a second referential view showing the state in use thereof.

The broken lines shown in the drawings represent portions of the cutting tool that form no part of the claimed design.
